DESIGN FOR A COMBINED HAIR WINDING KEY AND SMOOTHING PIN

Herman C. Schlicker, Brooklyn, N. Y., assignor to Clairol, Incorporated, Stamford, Conn., a corporation of Connecticut

Application February 14, 1942, Serial No. 195,792

Term of patent 3½ years

To all whom it may concern:

Be it known that I, Herman C. Schlicker, a citizen of the United States and a resident of Brooklyn, in the county of Kings and State of New York, with a post-office address at No. 375 Fairfield Avenue, Stamford, Connecticut, in care of Clairol, Incorporated, have invented a new, original, and ornamental Design for a Combined Hair Winding Key and Smoothing Pin, of which the following is a specification, reference being had to the accompanying drawing, forming part thereof, in which—

I claim:

The ornamental design for a combined hair winding key and smoothing pin, as shown.

HERMAN C. SCHLICKER,
